UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,845, dated March 4, 1884

Application filed January 28, 1884. Term of patent 3½ years.

To all whom it may concern:

Be it known that I, HENRY HUNT, of Greenville, in the State of New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

The ground is filled in with various fan-like, mural, and geometric ornamentation of small size, having a larger hexagonal and several square figures prominent but irregularly disposed. On this ground are three flower

groups. The largest of these groups is shown 20 in the center of the photograph. It has a large fan-like figure above, partly concealed, and various open flowers and projecting leaves and flower clusters loosely massed. Another group is shown at the left center and the right 25 upper and lower corners of the photograph. It is a similarly-massed group of flowers and leaves without the fan-like figure. The smallest group is shown at the left of the photograph, above and below. 30

I claim--

The design for a carpet, substantially as shown and described.

HENRY HUNT.
